UNITED STATES PATENT OFFICE

JOHN A. DOLAN, OF OAKLAND, CALIFORNIA

CLEANING DEVICE

Application filed October 23, 1929. Serial No. 401,862.

This invention relates to an improved cleaning device, an object of the invention being to provide a cleaning device, which includes the provision of a ball or spherical, 5 resilient, flexible member such as rubber, adapted to connect to a handle of the desired length, and having radially projecting lugs or fingers, preferably integral with the ball or sphere, so that a rubbing and cleaning action may be had in all directions by the manipulation of the device.

A further object is to provide a device of this character which can be utilized for many purposes such as cleaning toilets, pipes or for 15 many other uses, which can be manufactured and sold at a reasonably low price, and which will be most efficient in the performance of its functions.

The invention consists in certain novel features of construction and combinations and arrangements of parts, all of which will be more fully hereinafter described and pointed out in the claim.

In the accompanying drawings—
25 Figure 1 is a view in elevation illustrating my improved device;

Figure 2 is a view in longitudinal section through the ball or sphere, constituting the head of my improved cleaning device, with 30 the handle shown in elevation;

Figure 3 is a view in section on the line 3—3 of Figure 1.

My improved cleaning device comprises a spherical body 1, preferably of rubber or 35 other similar resilient flexible material, having radially projecting lugs or fingers 2 of the same material as the body and preferably integral therewith, so that from the surface of the body throughout its surface these 40 lugs or fingers project radially in all directions.

The body 1 is adapted to be connected to a handle 3 of any suitable material and length, and one means for connecting the 45 body to the handle is illustrated, that is, a socket 4 is provided in the body 1 into which the tapering end 5 of the handle is projected and held either by the gripping action of the body or secured thereto in any approved 50 manner.

A device of this kind when manipulated in a given space causes the resilient flexible lugs or fingers 2 to exert a rubbing action in all directions, and this action may be had by a longitudinal movement of the handle or by a 55 rotary movement of the handle, so that the device may be located in any certain place and given a rotary and longitudinal movement so as to thoroughly clean and dislodge any foreign matter.

While I show the lugs or fingers 2 as of general cylindrical form having blunt ends, I would have it distinctly understood that I do not limit myself to the particular shape of said lugs but may make such lugs of any 60 shape desired.

Various changes and alterations might be made in the general form of the parts described without departing from my invention and hence I do not limit myself to the precise details set forth but consider myself at 70 liberty to make such changes and alterations as fairly fall within the spirit and scope of the appended claim.

I claim:

A cleaning device, including a spherical shaped body of flexible resilient material adapted to be connected to a handle and having integral lugs or fingers projecting radially from the body in all directions.

JOHN A. DOLAN.
